CODED SIGNALING APPARATUS

Bernard E. O'Hagan, deceased, late of Swissvale, Pa., by Clare O'Hagan, administratrix, Swissvale, Pa., and Paul N. Martin, Penn Township, Allegheny County, Pa., assigns to The Union Switch and Signal Company, Swissvale, Pa., a corporation of Pennsylvania

Application August 6, 1947, Serial No. 766,502

13 Claims. (Cl. 246—34)

1

This invention relates to coded signaling apparatus, and particularly to improved means for producing coded impulses of energy suitable for use in coded signaling systems.

In systems of the type described, it has been the practice to code the supply of energy by means of a recurrently operated contact of a transmitting relay or other device. Due to mechanical limitations imposed by the necessity for fast operation, low operating power consumption, etc., it is necessary that these contacts be of a light duty construction. As a consequence, where conditions are encountered in which the amount of power controlled by these contacts becomes relatively great, the contacts are unable to withstand the heavy loads imposed upon them in interrupting a current of relatively high amperage, and their life is considerably decreased.

It is an object of this invention to provide improved means for supplying impulses of energy to a coded signaling system.

Another object of this invention is to provide improved means of the type described, in which the power load is governed by grid-controlled rectifier tubes which are controlled by the contacts of the coding device or transmitting relay.

A further object of this invention is to provide improved means for alternately connecting across the rails of a track section a code-following relay and a pair of conductors to which energy may be supplied from a source, in which the supply of energy from the source to the conductors is interrupted before the connections of the conductors to the track rails are interrupted to connect the code-following relay to the rails.

Another object of this invention is to provide means for insuring that large amounts of current supplied to a load from a source through contacts of relays will be interrupted prior to the opening of the contacts and will be established only after the closing of the contacts.

A further object of the invention is to provide in a coded signaling system means for recurrently connecting a pair of conductors to the secondary winding of a transformer, together with means for controlling the circuit of the transformer primary winding so that the supply of energy to the transformer primary winding is interrupted before the circuit from the transformer secondary winding to said conductors is interrupted.

In practicing this invention there is provided a first and a second code-transmitting relay which have contacts which are operated between a first and a second position substantially in synchronism. When the contacts of the first code-transmitting relay move to their second position they establish circuits for rendering electron tubes conducting and for supplying energy through these tubes to a pair of conductors. At

this time the contacts of the second code-transmitting relay establish a circuit in multiple with the circuit established by the contacts of the first code-transmitting relay for supplying energy through the electron tubes to the conductors. On movement of the contacts of the first code-transmitting relay away from their second position the electron tubes are rendered non-conducting, while the second code-transmitting relay thereafter maintains the circuit for supplying energy through the electron tubes to the conductors until the tubes cease to be conducting.

Since the second code-transmitting relay establishes a circuit for supplying energy through the electron tubes to the conductors at the time the contacts of the first code-transmitting relay interrupt the circuit which they control for supplying energy through these tubes to the conductors and as the contacts of the second code-transmitting relay do not interrupt the circuit for supplying energy through the electron tubes to the conductors until after the tubes have ceased to be conducting, it follows that the contacts of neither of the code-transmitting relays are required to interrupt the supply of energy to the conductors. Hence the relay contacts are not subjected to the arcing and burning which would occur if current were supplied through the contacts at the time they are opened, and the life of the contacts is therefore greatly increased.

In addition, when the contacts of both of the code-transmitting relays are in their first position a code-following relay is connected across the conductors over a circuit which includes contacts of the two transmitting relays in series so that this code-following relay is not connected with the conductors until the supply of energy to the conductors is cut off.

Other objects of the invention and features of novelty will be apparent from the following description taken in connection with the accompanying drawings.

Two forms of coded signaling apparatus embodying this invention will be described and the novel features thereof shall then be pointed out in claims.

In the accompanying drawings,

Fig. 1 is a diagrammatic view of a portion of a coded track circuit railway signaling system having means embodying our invention for supplying impulses of energy to the rails, and

Fig. 2 is a fragmentary view of a modification of Fig. 1.

Similar reference characters refer to similar parts in each of the two views.

Referring to Fig. 1, there is shown therein a section of railway track T having track rails 1 and 2 which are isolated from the rails of the adjacent section by the usual insulated joints 3. Traffic normally moves through the section T in

the direction indicated by the arrow, that is, from left to right as viewed in the drawings.

A signal S, which as shown is of the color-light type having a green lamp G, a yellow lamp Y, and a red lamp R, is located at the left-hand or entrance end of the section T and governs movements of traffic into the section T.

The signal S is controlled by master code energy fed from the right-hand or exit end of section T, and it is assumed that at the exit end of section T it is desired to provide a relay which is responsive to the occupancy of the section T, and is operated by coded feed back energy supplied from the entrance end of section T.

The equipment at the entrance end of section T comprises a code-following track relay TR, which is of a type the contacts of which are biased to their lower or released position and pick up when and only when energy flows through the winding in the direction indicated by the arrow, that is, from left to right; an impulse relay IR; an impulse transformer IT; a decoding transformer DT; a code-detecting relay HR, which is of a type the contacts of which are slightly slow in picking up and releasing; a decoding unit 180DU which supplies energy to a decoding relay DR; and a feed back battery IB.

At the exit end of section T, the equipment comprises a code following approach relay AR, which is of a type similar to the track relay TR; a first code-transmitting relay CTPR; a second or repeater code-transmitting relay CTPPR; code transmitters 180CT and 75CT; a control relay CR; a decoding transformer AT, which is similar to the decoding transformer DT, an approach repeater relay APR, which is of a type which is slow in picking up and releasing its contacts; a track rectifier TRX fed by a track transformer TT; a power transformer PT; a time element relay TER; a limiting impedance R3; and a pair of thyratron tubes VA and VB, with their associated condensers Ca and Cb and their associated resistors Ra and Rb.

At each end of section T, in addition to the apparatus named above, there is provided a source of direct current, not shown, the positive and negative terminals of which are designated B and C, respectively. Additionally, at the exit end of section T, there is provided a source of alternating current, not shown, whose terminals are designated BX and CX.

The thyratron tubes VA and VB are of a well-known type, each having a cathode 20, a heater 21, a grid 22, and a plate or anode 23, all enclosed in a gas-filled envelope. Tubes of this type are characterized by low voltage drop between anode and cathode, high current handling capacity, and by the fact that the current cannot be controlled by the grid potential after conduction through the tube is once initiated. The conduction can only be stopped by reducing the potential between anode and cathode to a value below the ionization voltage of the gas enclosed in the tube.

Power for the heaters 21 of tubes VA and VB, and bias voltages for the grids 22 of tubes VA and VB are obtained from the power transformer PT, which has its primary winding 24 continuously connected to the source of alternating current energy. A secondary winding 26 provides alternating current for the heaters 21 of tubes VA and VB through the connection designated X and Y. Energy is also supplied from winding 26 to the time element relay TER, which is of a type the contacts of which when released will pick up

only after a predetermined time has elapsed after energy is supplied to the relay winding. A front contact 28 of relay TER governs the supply of alternating current energy to the anode-cathode circuits of tubes VA and VB so that in the event that the supply of energy to the primary winding of transformer PT is cut off and is thereafter restored, energy will not be supplied to the anode-cathode circuits of tubes VA and VB until sufficient time has elapsed for the heaters 21 of tubes VA and VB to heat the cathodes to proper operating temperature.

The grid 22a of tube VA is provided with an alternating current bias voltage by the circuit including secondary winding 30 of transformer PT, and the grid 22b of tube V2 is provided with an alternating current bias voltage by the circuit including secondary winding 32 of transformer PT.

When the instantaneous polarity of the alternating current source is such that terminal BX is positive with respect to terminal CX, the cathode 20a of tube VA is positive with respect to the anode 23a of tube VA, and current cannot flow through tube VA. At this time the anode 23b of tube VB is positive with respect to its cathode 20b and if the grid 22b of tube VB is also positive, tube VB will conduct. However the secondary winding 32 of transformer PT is constructed and arranged so that when the anode or plate 23b of tube VB has a positive potential, the grid 22b of tube VB will have a negative potential with respect to the cathode 20b, and as a result the tube VB will not conduct.

When the instantaneous polarity of the alternating current source is such that terminal CX is positive with respect to terminal BX, the anode 23a of tube VA is positive and its cathode 20a is negative. However, the polarity of the energy supplied from the secondary winding 30 of transformer PT is such that the grid 22a of tube VA has a negative potential with respect to the cathode 20a, and as a result, tube VA will not conduct. Also, at this time the cathode 20b of tube VB has a positive potential with respect to its anode 23b and tube VB will not conduct.

From the foregoing it will be seen that the apparatus is arranged so that when the contacts of relay CTPR are open the polarity of energy supplied to the anodes of tubes VA and VB together with the polarity of bias voltage applied to their grids is such that the tubes normally will not conduct.

When front contact 36 of relay CTPR is closed, it establishes a direct connection between the grid 22a and cathode 20a of tube VA, and when front contact 38 of relay CTPR is closed, it establishes a direct connection between the grid 22b and cathode 20b of tube VB. As a result, the bias potential between the grid and cathode of each tube is reduced to zero, and the tubes will fire, tube VA firing during the half cycle of the alternating current when terminal CX is positive with respect to terminal BX, and tube VB firing during the other half cycle of the alternating current when terminal BX is positive with respect to terminal CX. The primary winding 40 of transformer TT is connected across the terminals BX and CX of the source of alternating current through the tubes VA and VB in parallel so that energy from the source is supplied to the transformer primary winding through the tubes from the source when the tubes are conducting. Energy supplied to the primary winding of transformer TT induces alternating current in the

transformer secondary winding 42. This alternating current is rectified by the full-wave rectifier TRX, and the resulting direct current energy is fed to the exit end of track section T in a manner to be subsequently described.

When the contacts 36 and 38 of relay CTPR release, the bias voltage is again supplied to the grids of tubes VA and VB, and if the alternating current is near the end of a half cycle at the time, the tubes will stop conducting at once. If the bias voltage is supplied during the conducting portion of a half cycle, when the current is high, the tube which is to pass current will continue firing until the end of that half cycle, and will then be extinguished.

The limiting impedance R3 serves to limit to a safe value the flow of current through the tubes VA and VB and the current in the secondary circuit including rectifier TRX, while the tubes are conducting and track section T is occupied by a train.

The condenser Ca and resistor Ra in the grid circuit of tube VA serve to provide a small direct current bias component on the grid 22a of tube VA when tube VA is not firing. When the grid 22a of tube VA has a positive potential, a small amount of grid current will flow between the grid 22a of tube VA and the cathode 20a. This flow of current through the resistor Ra causes a voltage drop across the resistor, and as a result the condenser Ca is charged. At this time the flow of current through resistor Ra will be from left to right, with the result that the element of condenser Ca which is connected to the grid 22a of tube VA will have a negative potential with respect to the other element of the condenser. When the grid 22a of tube VA changes polarity the negative charge of the condenser Ca establishes a direct current negative bias on the grid, since the negative potential is on the element of the condenser which is connected to the grid of the tube. The direct current negative bias thus supplied to the grid of tube VA serves to prevent false firing of the tube due to transient surges in the supply of alternating current to the apparatus.

Condenser Cb and resistor Rb in the grid circuit of tube VB function in a similar manner to that described above for condenser Ca and resistor Ra and a detailed explanation of their operation is unnecessary.

If the supply of alternating current to the transformer PT be interrupted for any reason, the supply of energy from secondary winding 26 of transformer PT to the heaters 21 of tubes VA and VB and to the winding of relay TER will be cut off. As a result, front contact 28 of relay TER will release and thereby interrupt the supply of energy to the anode-cathode circuits of tubes VA and VB, to thereby prevent the supply of energy through the tubes while the heaters in the tubes are not properly heated.

When the supply of alternating current energy is restored to transformer PT, the secondary winding 26 again supplies energy to the heaters 21 of tubes VA and VB. However, the anode-cathode circuits of tubes V1 and V2 remains interrupted by front contact 28 of relay TER until a certain time has elapsed after energy is again supplied to the relay winding, for example, 30 seconds. During this time the heaters will have raised the temperature of the cathodes to their operating point. After this time interval has elapsed, front contact 28 of relay TER picks up and thereafter remains picked up, thereby restor-

ing the supply of energy to the anode-cathode circuits of tubes VA and VB. The characteristics of the type of tubes used in this arrangement are such that if energy is supplied to the anode-cathode circuit of a tube before the cathode of the tube is sufficiently hot, deleterious results may occur, and it is necessary therefore to provide some type of time delay between the supply of energy to the heaters of the tubes and the supply of energy to their anode-cathode circuits.

It is to be understood that various other means of obtaining the time delay may be used in connection with this invention, the means shown herewith being one type which may be used.

From the foregoing it will be seen that each time the contacts of relay CTPR pick up, the bias is removed from the grids of the tubes VA and VB and they will then fire during alternate half cycles of the alternating current supplied to them, and when the contacts of relay CTPR release, the bias is restored to the grids of the tubes so that they stop firing. Accordingly, the contacts of relay CTPR have only to interrupt the grid bias energy, while the thyratron tubes interrupt the heavier load of the energy supplied to the transformer TT.

The equipment is shown in the drawings in its normal condition, with track section T unoccupied. Code transmitters 180CT and 75CT operate continuously, the contacts of code transmitter 180CT being operated at a frequency of 180 complete cycles per minute, while the contacts of code transmitter 75CT are operated at a frequency of 75 complete cycles per minute. As shown, the control relay CR, which may be controlled in any suitable manner by traffic conditions in advance of section T, is picked up, and when the contacts of code transmitter 180CT pick up, a circuit is established to supply energy to the relay CTPR. This circuit is traced from terminal B, over front contact 10 of code transmitter 180CT, front contact 12 of relay CR, and through the winding of relay CTPR to terminal C.

When the contacts of relay CTPR pick up, its contact 14 establishes a circuit to supply energy to the winding of relay CTPPR. Accordingly, at this time, when contact 10 of code transmitter 180CT picks up, relay CTPR picks up and shortly thereafter relay CTPPR picks up. Similarly, each time contact 10 of code transmitter 180CT releases, the contacts of relay CTPR release and interrupt the circuit of relay CTPPR, and shortly thereafter the contacts of relay CTPPR release.

When relay CTPR picks up to close its contacts 36 and 38 in the circuits of the grids of tubes VA and VB, contact 50 in the circuit for supplying energy from the rectifier TRX to the track rails is closed. The contacts 36, 38 and 50 operate substantially in synchronism and will close at or substantially at the same time so the circuit for supplying energy from the rectifier TRX to the track rails is closed at the time the tubes VA and VB become effective to supply energy to the circuit of the rectifier TRX. When contact 59 of relay CTPR picks up it opens the circuit of relay AR, while when contact 14 of relay CTPR closes energy is supplied to relay CTPPR and its contacts pick up with the result that contact 48 of relay CTPPR establishes a connection shunting contact 50 of relay CTPR, and contact 58 additionally interrupts the circuit of relay AR.

As previously explained, when the contacts 36 and 38 of relay CTPR pick up, the thyratron tubes VA and VB fire, and energy is supplied to the rec-

ifier TRX from the secondary winding 42 of transformer TT. The resulting direct current energy is supplied to the track relay TR at the entrance end of the section T by a circuit which is traced from the positive terminal of the rectifier TRX, through the wire 44 to section rail 1, through section rail 1, through the winding of relay TR from left to right, over back contact 46 of relay IR, which is released at this time, through section rail 2, and over front contact 48 of relay CTPR and front contact 50 of relay CTPR in multiple to the negative terminal of rectifier TRX. The polarity of this energy is such that the contacts of relay TR pick up.

On picking-up of the contacts of relay TR, contact 52 establishes a connection from terminal B of the source to the left-hand terminal of the primary winding 54 of transformer IT. The center terminal of this winding is connected to terminal C of the source so that one-half of the transformer winding is energized and an impulse of energy is induced in the transformer secondary winding 56, and is supplied therefrom to the winding of relay IR. However, relay IR is of a type the contacts of which become picked up only when energy of one polarity is supplied to the winding and the various parts of the equipment are arranged so that the energy supplied to the relay IR on movement of the contacts of relay TR to their picked-up positions is of such polarity as to be ineffective to pick up the contacts of relay IR.

After a brief time interval, contact 10 of code transmitter 180CT opens, thereby interrupting the supply of energy to relay CTPR. When relay CTPR releases, its contact 44 interrupts the circuit of relay CTPR but this relay is snubbed by a resistor and its contacts remain picked up for a short time subsequent to interruption of the supply of energy to the relay winding. This time interval is long enough to insure that contact 48 of relay CTPR continues to maintain the circuit for connecting rectifier TRX to the track rails until after the tubes VA and VB cease to be conducting. Accordingly, when contact 50 of relay CTPR releases, the circuit for supplying energy from rectifier TRX to the section rails 1 and 2 is maintained by contact 48 of relay CTPR, so that the current flowing in the circuit is not interrupted by the contact 50 of relay CTPR. When contacts 36 and 38 of relay CTPR release, the bias is restored to the grids of tubes VA and VB, as explained above, and the tubes stop firing within a half-cycle of the alternating current supply. As a result, the energy supplied to rectifier TRX from the transformer TT is interrupted, and the supply of direct current energy from the rectifier TRX to the track rails is cut off.

Shortly thereafter, the contacts of relay CTPR release, the supply of energy to the winding of relay CTPR having been interrupted by the release of contact 44 of relay CTPR. Since the supply of energy from rectifier TRX is interrupted by tubes VA and VB as a result of the release of the contacts of relay CTPR, the supply of energy to the section rails has already been interrupted when front contact 48 of relay CTPR opens, and as a consequence, the contact 48 is not required to open the circuit under load.

When the contacts of relay CTPR and relay CTPR are released the approach relay AR is connected across the section rails 1 and 2 by a circuit including back contact 50 of relay CTPR and back contact 58 of relay CTPR.

On the interruption of the supply of energy

from rectifier TRX, the contacts of relay TR release and contact 52 thereupon establishes a circuit to energize the right-hand portion of the primary winding 54 of transformer IT. As a result, an impulse of energy is induced in the transformer secondary winding 56 and this impulse is of a polarity opposite to that of the impulse present on movement of the contacts of relay TR to their picked-up positions. Accordingly, the energy supplied to the winding of relay IR is effective to momentarily pick up the contact of this relay.

On picking up of relay IR its contact 46 interrupts the circuit traced above for connecting the winding of the relay TR across the track rails and establishes a circuit to supply energy from the battery IB over the section rails 1 and 2 to the winding of relay AR. This circuit is traced from the positive terminal of battery IB over front contact 46 of relay IR, through the section rail 2, over back contact 50 of relay CTPR, through the winding of relay AR from left to right, over back contact 58 of relay CTPR, and through wire 44 and section rail 1 to the negative terminal of battery IB. The polarity of the energy supplied to relay AR is such that it is effective to pick up the contacts of the relay AR.

After a brief time interval the relay IR releases and its contact 46 interrupts the supply of energy from the battery IB to the relay AR, and reconnects the track relay TR across the section rails 1 and 2.

Subsequently, contact 10 of code transmitter 180CT closes, and again supplies energy to relay CTPR which picks up and thereby interrupts the circuit connecting relay AR to the section rails and again establishes the circuit for firing the thyratrons VA and VB in addition to establishing the circuit for connecting the rectifier TRX to the section rails and the circuit for energizing relay CTPR.

As long as the track section T is vacant, the equipment continues to operate in this manner. Energy is supplied to the track relay TR over the rails of section T from the rectifier TRX 180 times per minute, and during the "off" intervals energy is supplied over the section rails to the relay AR from battery IB.

Relay TR has associated therewith a code detector relay HR which is energized by current supplied through a decoding transformer DT when and only when the track relay follows coded energy, as explained in Letters Patent of the United States No. 2,237,783 to Frank H. Nicholson et al.

A secondary winding 60 on transformer DT supplies energy to the decoding-relay DR through the resonant rectifier unit 180DU, well-known in the railway signaling art, which is arranged and constructed so that it will supply to relay DR energy of sufficient value to pick up the relay contacts when and only when energy is supplied to the decoding unit at a frequency of 180 cycles per minute from the decoding transformer DT.

At this time the contacts of relay TR are operated 180 times per minute in response to the impulses of energy supplied from the exit end of section T, and as a result the contacts of relays HR and DR are picked up, and the green lamp G of signal S is supplied with energy at this time by the obvious circuit including front contact 66 of relay HR and front contact 70 of relay DR.

Approach relay AR located at the exit end of the section T has associated therewith an approach-repeater relay APR which is energized by current supplied through a decoding transformer

AT when and only when the relay AR follows coded energy, as explained above in connection with relay HR. The contacts of relay AR are operated at this time by impulses of feed back energy from the battery IB, and accordingly, the contact 72 of relay APR is picked up, showing that section T is unoccupied.

It will now be assumed that a train moving from left to right passes signal S and enters section T. The wheels and axles of the train shunt the impulses of master code energy from the winding of relay TR, and its contacts release and remain released. As a result, energy is no longer supplied to the windings of relays HR and DR, and these relays release, interrupting the supply of energy to the green lamp G and establishing an obvious circuit for supplying energy to the red lamp R of signal S.

Additionally, contact 46 of impulse relay IR remains released so that impulses of feed back energy are no longer supplied to track section T from the feed back battery IB, and as a result the contacts of relay AR remain released. Accordingly, relay APR is no longer supplied with energy from transformer AT, and its contact 72 releases, to thereby indicate the occupancy of section T.

During occupancy of section T the equipment at the exit end of the section continues to operate as explained above to supply impulses of energy through the rectifier TRX to the track rails. Because of the shunting effect of the train the value of the impulses supplied to the rails increases as the train approaches the exit end of the section. However, as explained above, the supply of energy to the track rails is always interrupted by the tubes VA and VB and not by the contacts of relays CTPR and CTPPR. Accordingly, even though the section is occupied for a considerable period, the contacts of relays CTPR and CTPPR will not be damaged, as might be the case if the contacts of these relays were required to interrupt the supply of energy to the track rails.

When the train under consideration enters the section in advance of section T, the relay CR releases and transfers control of relay CTPR from the code transmitter 180CT to the code transmitter 75CT. Except for the change in the rate of operation of the relays CTPR and CTPPR the equipment operates as described above.

When the train vacates section T, impulses of master code energy supplied to the track rails again feed to track relay TR, and as a result of the operation of its contacts, energy is again supplied through transformer DT to relay HR, and its contacts pick up. At this time, however, control relay CR is released, and its back contact 73 establishes the circuit including contact 74 of code transmitter 75CT for supplying energy to the winding of relay CTPR. Accordingly, the relay CTPR operates its contacts 75 times per minute, and impulses of master code energy are supplied at this rate to track relay TR through section rails 1 and 2. The operation of the contacts of relay TR supplies energy to relay HR through the decoding transformer DT, and the contacts of relay HR pick up, but since the frequency of the energy now supplied from transformer DT is 75 cycles per minute, relay DR is not supplied with sufficient energy to pick up its contacts, and its contacts remain released. When relay HR picks up a circuit is established over its front contact 68 and back contact 70 of relay DR to supply energy to the yellow lamp Y of signal S.

Additionally, each time contact 52 of track relay TR releases, relay IR picks up momentarily

to supply an impulse of feed back energy from the feed back battery IB to relay AR through section rails 1 and 2 and over back contact 50 of relay CTPR and back contact 58 of relay CTPPR. The code following operation of relay AR supplies energy to relay APR through the decoding transformer AT and the contact 72 of relay APR picks up to show that section T is unoccupied.

As the train under consideration progresses farther, the contacts of relay CR pick up, and its front contact 12 establishes the circuit for controlling relay CTPR over contact 10 of code transmitter 180CT. As a result, the contacts of relays CTPR and CTPPR operate 180 times per minute, and impulses of master code energy are supplied to track relay TR over section rails 1 and 2 at this rate. The contacts of track relay TR now operate 180 times per minute, and as a result the energy supplied to relay DR from decoding unit 180DU is of a value sufficient to pick up the contacts of the relay. When contact 70 of relay DR picks up, it cooperates with contact 68 of relay HR to establish the circuit for supplying energy to the green lamp G of signal S.

Additionally, relay IR operates 180 times per minute to supply impulses of feed back energy from the feed back battery IB to the relay AR, and as a result relay APR remains energized.

The equipment is now restored to its normal condition as originally described.

In Fig. 2 there is shown a fragmentary view of a modification of the equipment shown in Fig. 1, wherein the winding of relay CTPPR is directly connected across the output terminals of the rectifier TRX, so that as long as energy is supplied through rectifier TRX, relay CTPPR will be picked up. The remainder of the apparatus is arranged in a manner similar to that shown in Fig. 1.

In operation, when relay CTPR picks up, its contact 59 establishes the circuit for supplying energy from the rectifier TRX to the track rails 1 and 2 of section T and interrupts the circuit for connecting the winding of relay AR across the rails of section T. When contacts 36 and 38 of relay CTPR pick up, the tubes VA and VB are rendered conducting, as explained in detail in connection with Fig. 1. As a result, energy is supplied through the rectifier TRX to the track rails 1 and 2 of section T, and additionally to the winding of relay CTPPR. When contact 48 of relay CTPPR picks up, it establishes a circuit in multiple with front contact 50 of relay CTPR for supplying energy to the rails of section T, and when contact 58 of relay CTPPR picks up, it additionally interrupts the circuit of the winding of relay AR.

When relay CTPR releases, its contact 50 interrupts the connection previously established for supplying energy from the rectifier TRX to the rails of section T, but the additional connection established by contact 48 of relay CTPPR is maintained at this time, so that contact 50 is not required to interrupt the flow of energy. When contact 50 of relay CTPR releases, it again establishes one portion of the circuit for connecting relay AR across the rails of section T, but this circuit remains interrupted at this time by contact 58 of relay CTPPR. When contacts 36 and 38 of relay CTPR release, the tubes VA and VB are rendered non-conducting and accordingly, the supply of energy through the rectifier TRX to the rails of section T and to the winding of relay CTPPR is cut off. When relay CTPPR releases, its contact 48 interrupts the circuit for connecting

the rectifier TRX to the section rails, and contact 58 of relay CTPPR completes the circuit for connecting the winding of relay AR across the section rails. The recurrent operation of the contacts of relay CTPR cause a repetition of the cycle described above. Accordingly, it will be seen that each time relay CTPR picks up, the winding of relay AR is disconnected from the rails of section T, and energy is supplied to the rails of section T from rectifier TRX as a result of tubes VA and VB being rendered conductive by the picking up of the contacts of relay CTPR. When energy is supplied from rectifier TRX, the relay CTPPR picks up, and front contact 48 of relay CTPPR establishes an additional circuit for connecting the rectifier TRX across the rails of section T, while back contact 58 of relay CTPPR additionally interrupts the circuit for connecting relay AR across the section rails. When relay CTPR releases, its contact 50 interrupts one circuit for supplying energy to the rails of section T from the rectifier TRX, but front contact 48 maintains its circuit, so that the supply of energy is not interrupted by contact 50 of relay CTPR. When contacts 36 and 38 of relay CTPR release, the tubes VA and VB become non-conductive and as a result, energy is no longer supplied to the rails of section T and the winding of relay CTPPR, and relay CTPPR releases, thereby interrupting the connection from the rectifier TRX to the track rails and connecting the relay AR to the rails. Since relay CTPPR releases when and only when the supply of energy through the rectifier ceases, it is clear that contact 48 of relay CTPPR is not required to open the circuit of the rectifier while energy is being supplied through the rectifier.

An advantage of the arrangement shown in Fig. 2 is that if by some derangement or failure, the tubes VA and VB continuously conduct, the relay CTPPR will obviously be continuously energized, and thereby cause a continuous supply of energy to the rails of section T. In a system such as that shown in the drawings, the continuous supply of energy to the code following track relay will cause the signal to display its stop aspect, and thereby indicate improper operation of the equipment.

Additionally, since relay CTPPR would be continuously energized under such circumstances, contact 58 of relay CTPR would not be required to make and break the circuit for supplying energy to the rails of section T, so that the contact 50 would not be subject to arcing and other adverse effects. Also, contact 58 of relay CTPPR would continuously interrupt the circuit for connecting relay AR to the section rails, and as a result, relay APR would release and remain released, to also indicate improper operation of the equipment.

It will be seen from the foregoing that the arrangement of apparatus comprising this invention is such that large amounts of power may be supplied to a coded type of signaling system without adverse effects on the contacts of the controlling relays. It will be apparent to those skilled in the art that the arrangement of apparatus is not limited to that shown, but may be applied to various types of coded signaling systems, for example, in the arrangement shown in Fig. 1, the feed back battery IB may be replaced by an arrangement similar to that shown for supplying master code energy. Also, the rectifier TRX may be omitted and the alternating current energy supplied from the secondary 42 of transformer TT may be supplied to the track

section T to provide an alternating current coded track circuit system, or a half-wave rectifier may be substituted for the full-wave rectifier TRX to provide pulsating direct current energy for track section T.

Although there are herein shown and described only two forms of coded signaling apparatus embodying this invention, it is understood that various changes and modifications may be made therein within the scope of the appended claims without departing from the spirit and scope of this invention.

Having thus described our invention, what we claim is:

1. In a coded signaling system, a pair of conductors, a first transmitting relay having contacts recurrently operated between a first and a second position, a second transmitting relay having contacts which are operated to a first or a second position according as the contacts of said first transmitting relay are in their first or their second position, a transformer, circuit means for connecting said conductors to the terminals of the secondary winding of said transformer when the contacts of at least one of said transmitting relays are in their second position, means for connecting the primary winding of said transformer to a source of alternating current in series with a first electron tube capable of permitting flow of energy of one polarity and a second electron tube capable of permitting flow of energy of the other polarity, and control means for each of said tubes governed by a contact of said first transmitter relay and arranged to cause said tubes to be conducting when and only when the contacts of said first transmitter relay occupy their second position.

2. In a coded track circuit signaling system, a section of railway track, a first transmitting relay having contacts operated between a first and a second position at a selected code rate, a second transmitting relay having contacts which are operated to a first or a second position according as the contacts of said first transmitting relay are in their first or their second position, a track transformer, circuit means for connecting the rails of said section with the terminals of the secondary winding of said track transformer when the contacts of at least one of said transmitting relays are in their second position, means for connecting the primary winding of said track transformer with a source of alternating current in series with a first electron tube capable of permitting flow of energy of normal polarity and a second electron tube capable of permitting flow of energy of reverse polarity, and control means for each of said tubes governed by a contact of said first transmitter relay and arranged to cause said tubes to be conducting when and only when the contacts of said first transmitter relay occupy their second position, and a circuit including a first position contact of said first transmitting relay and a first position contact of said second transmitting relay connected in series for connecting the rails of said section to the winding of a code-following relay.

3. In a coded track circuit signaling system, in combination, a section of railway track, a first transmitting relay having contacts operable between a first and a second position at a selected code rate, a second transmitting relay having contacts which are moved to a first or a second position according as the contacts of said first transmitting relay are in their first or their second position, circuit means for connect-

ing the rails of said section to a source of energy when the contacts of at least one of said transmitting relays are in their second position, said source comprising a source of alternating current, a pair of electron tubes, a transformer having a primary winding connected in series with said tubes and said source, control means for each of said tubes governed by a contact of said first transmitting relay and arranged to cause said tubes to be conducting when and only when the contacts of said first transmitting relay occupy their second position, said second transmitting relay being constructed and arranged so that the time required for the contacts of the relay to operate from their second to their first position is longer than one half of a complete cycle of said alternating current source.

4. In a coded track circuit signaling system, in combination, a section of railway track, a first transmitting relay having contacts operable between a first and a second position at a selected code rate, a second transmitting relay having contacts which are moved to a first or a second position according as the contacts of said first transmitting relay are in their first or their second position, circuit means for connecting the rails of said section to a source of energy when the contacts of at least one of said transmitting relays are in their second position, said source comprising a source of alternating current, a pair of electron tubes, a transformer having a primary winding connected in series with said tubes and said source, control means for each of said tubes governed by a contact of said first transmitting relay and arranged to cause said tubes to be conducting when and only when the contacts of said first transmitting relay occupy their second position, said second transmitting relay being constructed and arranged so that the time required for the contacts of the relay to operate from their second to their first position is longer than one half of a complete cycle of said alternating current source, and a circuit including a first position contact of said first transmitting relay and a first position contact of said second transmitting relay connected in series for connecting the rails of said section to the winding of a code following relay.

5. In a coded track circuit signaling system, in combination, a section of railway track, a first transmitting relay having contacts operable between a first and a second position at a selected code rate, a second transmitting relay having contacts which are moved to a first or a second position according as the contacts of said first transmitting relay are in their first or their second position, circuit means for connecting the rails of said section to a source of energy when the contacts of at least one of said transmitting relays are in their second position, said source comprising a source of alternating current, a pair of electron tubes, and control means for each of said tubes governed by a contact of said first transmitting relay and arranged to cause said tubes to be conducting when and only when the contacts of said first transmitting relay occupy their second position.

6. In a coded track circuit signaling system, in combination, a section of railway track, a first transmitting relay having contacts operable between a first and a second position at a selected code rate, a second transmitting relay having contacts which are moved to a first or a second position according as the contacts of said first

transmitting relay are in their first or their second position, circuit means for connecting the rails of said section to a source of energy when the contacts of at least one of said transmitting relays are in their second position, said source comprising a source of alternating current, a pair of electron tubes, and control means for each of said tubes governed by a contact of said first transmitting relay and arranged to cause said tubes to be conducting when and only when the contacts of said first transmitting relay occupy their second position and a circuit including a first position contact of said first transmitting relay and a first position contact of said second transmitting relay connected in series for connecting the rails of said section to the winding of a code following relay.

7. In a coded track circuit signaling system, a section of railway track, a first transmitting relay having contacts operated between a first and a second position at a selected rate, a second transmitting relay, means effective when the contacts of said first transmitting relay are moved to their second position to move the contacts of said second transmitting relay to their second position, means effective when the contacts of said first transmitting relay are moved to their first positions to move the contacts of said second transmitting relay to their first position after a predetermined time interval, a source of alternating current, a pair of electron tubes, control means for rendering said tubes conducting when the contacts of said first transmitting relay are in their second position, and a circuit over which energy may be supplied from said source through said tubes to the rails of said section of track when the contacts of at least one of said transmitting relays are in their second position.

8. In a coded signaling system, a pair of conductors, a first and a second transmitting relay each having contacts movable between a first and a second position, means for recurrently moving the contacts of said first transmitting relay between their first and their second position, a source of alternating current, a pair of electron tubes, control means for rendering said tubes conducting when the contacts of said first transmitting relay are in their second position, a circuit established when the contacts of at least one of said transmitting relays are in their second position and over which energy of one polarity may be supplied from said source through one of said tubes to said conductors and over which energy of the other polarity may be supplied from said source through the other of said tubes to said conductors, means operative when the contacts of said first transmitting relays are moved to their second position for moving the contacts of said second transmitting relay to their second position, and means operative when the contacts of said first transmitting relay are moved to their first position for causing the contacts of said second transmitting relay to move to their first position only after energy has ceased to be supplied from said source to said conductors, whereby the circuits for supplying energy from said source through said tubes to said conductors are not interrupted until after energy ceases to be supplied through said tubes.

9. In a coded signaling system, a pair of conductors, a first transmitting relay having contacts recurrently operated between a first and a second position, a transformer having a primary and a secondary winding, a second transmitting relay having a winding effectively connected across the

secondary winding of said transformer and having contacts which are biased to a first position and are moved to a second position when energy is supplied to said relay winding, circuit means for connecting said conductors to the terminals of the secondary winding of said transformer when the contacts of at least one of said transmitting relays are in their second position, means for connecting the primary winding of said transformer to a source of alternating current in series with a first electron tube capable of permitting flow of energy of one polarity and also in series with a second electron tube capable of permitting flow of energy of the other polarity, and control means for each of said tubes governed by a contact of said first transmitter relay and arranged to cause said tubes to be conducting when and only when the contacts of said first transmitter relay occupy their second position.

10. In a coded signaling system, a pair of conductors, a first transmitting relay having contacts recurrently operated between a first and a second position, a transformer having a primary and a secondary winding, a second transmitting relay having a winding effectively connected across the secondary winding of said transformer and having contacts which are biased to a first position and are moved to a second position when energy is supplied to said relay winding, circuit means for connecting said conductors to the terminals of the secondary winding of said transformer when the contacts of at least one of said transmitting relays are in their second position, means for connecting the primary winding of said transformer to a source of alternating current in series with a first electron tube capable of permitting flow of energy of one polarity and also in series with a second electron tube capable of permitting flow of energy of the other polarity, control means for each of said tubes governed by a contact of said first transmitter relay and arranged to cause said tubes to be conducting when and only when the contacts of said first transmitting relay occupy their second position, and a circuit including a first position contact of said first transmitting relay and a first position contact of said second code transmitting relay connected in series for connecting said conductors to the winding of a code following relay.

11. In a code transmitting and receiving means for a coded signaling system, in combination, a pair of conductors, an electron tube, a pair of supply wires over which energy may be supplied from a source of alternating current through said tube to said conductors, a first transmitter relay having contacts recurrently operated between a first and a second position, a second transmitter relay having contacts biased to a released position from which they are movable to a picked up position on the supply of energy to the relay winding, said second transmitter relay contacts being effective when in their picked up position to establish connection between said supply wires and said conductors, means for supplying energy from said supply wires to the winding of said second transmitter relay, means operative on movement of the contacts of said first transmitter relay to their second position to establish connection between said supply wires and said conductors and to render said tube conducting, and means for rendering said tube non-conducting.

12. In code transmitting and receiving means for a coded signaling system, in combination, a pair of conductors, a transformer, a pair of supply wires over which energy may be supplied from the secondary winding of said transformer to said conductors, a first transmitter relay having contacts recurrently operated between a first and a second position, a second transmitter relay having contacts movable between a first and a second position, means for establishing connection from said supply wires to said conductors when the contacts of either of said transmitter relays are in their second position, circuit means effective on movement of the contacts of said first transmitter relay to their second position to establish a circuit over which energy may be supplied from a source of alternating current to the primary winding of said transformer, and means for controlling said second transmitter relay so as to cause its contacts to move from their first to their second position before the contacts of said first transmitter relay move from their second to their first position and so as to cause the contacts of said second transmitter relay to move from their second to their first position only after the contacts of said first transmitter relay move to their first position.

13. In code transmitting and receiving means for a coded signaling system, in combination, a pair of conductors, a transformer, a first transmitter relay having contacts recurrently operated between a first and a second position, a second transmitter relay having contacts movable between a first and a second position, circuit means governed by a contact of said first transmitter relay for at times establishing a circuit over which energy may be supplied from a source of alternating current to the primary winding of said transformer and for at other times interrupting said circuit, a circuit including a contact of said second transmitter relay for connecting the secondary winding of said transformer across said conductors, a code following relay having a winding which at times is effectively connected across said conductors by a circuit governed by a contact of said second transmitter relay, and means for controlling said second transmitter relay so that its contacts maintain the circuit for connecting the secondary winding of said transformer across said conductors until after the supply of energy to the primary winding of said transformer has been interrupted and so that the winding of said code following relay is effectively connected across said conductors only when the circuit for connecting the secondary winding of said transformer across said conductors is interrupted.
